APPARATUS FOR PRODUCING CARPET
RETAINING STRIPS

Howard L. Newcomb, Fred E. Werner, Richard J. Myers, and Henry Laetari, Los Angeles County, Calif., assignors to Roberts Manufacturing Co., Los Angeles, Calif., a corporation of California

Application December 24, 1951, Serial No. 263,096

26 Claims. (Cl. 1-1)

1

This invention relates to a method and apparatus for forming carpet retaining strips or fasteners similar in nature to the carpet fastener disclosed in the United States Letters Patent No. 2,238,946, issued on April 22, 1941, to Roy M. Roberts.

Carpet retaining strips or fasteners manufactured in accordance with the aforementioned patent usually consist of elongated, relatively thin base strips having a plurality of fasteners inserted therein, the longitudinal axes of the fasteners being angularly inclined with respect to the horizontal upper surface of the base strip. Among the problems attendant on the manufacture of the aforementioned carpet fasteners are the handling of large numbers of relatively flexible base strips; the orientation of the base strips with their transverse axes disposed in planes angularly inclined with respect to horizontal planes; the conveyance of the base strips in an expeditious and efficient manner; the formation in the strips of fastener receiving holes; the prevention of the splintering of the strip when fasteners are driven therein; the driving of fasteners into the previously formed fastener receiving holes in such a manner that the longitudinal axes of the fasteners will be inclined with respect to the horizontal upper surface of the base strip when the fasteners are driven thereto; and insuring that the working ends of the fasteners protrude a predetermined distance above the upper face of the strip after the fasteners have been driven therethrough.

It is, therefore, a primary object of our invention to provide an apparatus for the manufacture of carpet fasteners which includes means for orienting the transverse axes of the base strips at angles to horizontal planes so that, when the fasteners are driven thereto with their longitudinal axes aligned with the vertical, their longitudinal axes will be disposed angularly with respect to the upper surface of the strip.

Another object of our invention is the provision of an apparatus for manufacturing carpet fasteners which includes an angularly disposed bed, the transverse axis of the bed being angularly disposed with respect to a horizontal plane, said bed being designed to receive the base strips of the carpet fasteners and to orient them with their transverse axes angularly inclined to the same horizontal plane as the bed.

Another object of our invention is the provision of an apparatus for manufacturing carpet fasteners which includes a bin juxtaposed to the

2

receiving end of the aforesaid bed, said bin being adapted to receive a plurality of superimposed base strips and being angularly inclined with respect to the vertical so as to orient the transverse axes of the strips deposited therein with the angular inclination of the bed associated with said bin.

A further object of our invention is the provision of an apparatus for forming carpet fasteners which includes conveyor means for translating said base strips along the aforesaid angularly inclined bed, said conveying means being designed to extract base strips from the aforementioned bin at the receiving end of said bed and to translate them along the entire length of the bed.

An additional object of our invention is the provision of conveying means of the aforementioned type which is intermittently operable so that the base strips are rendered momentarily immobile on the aforementioned bed to permit certain operations to be performed thereupon during the time in which the strips are not moving on said bed.

An additional object of our invention is the provision of an apparatus for manufacturing carpet fasteners which includes a vertically reciprocable carriage, said carriage being reciprocable between a first, uppermost position, and a second, lowermost position adjacent the aforementioned bed, and being mounted on a frame adjacent said bed to facilitate the reciprocation thereof with respect thereto.

A further object of our invention is the provision of an apparatus for manufacturing carpet fasteners in which the aforementioned reciprocable carriage is operatively connected to the conveying means of the apparatus, the reciprocating movement of the carriage causing the concomitant movement of said conveying means with respect to said bed.

An additional object of our invention is the provision of an apparatus of the aforementioned type wherein the operative connection between said carriage and said conveying means is of the "lost" motion type, permitting the conveying means to be rendered temporarily immobile while the movement of the carriage between the first and second positions thereof continues uninterrupted.

A further object of our invention is the provision of an apparatus of the aforementioned type in which the aforesaid "lost" motion connection is constituted, in part, by a cam mounted on the carriage and reciprocable therewith and

a cam follower associated with said conveying means and engageable with said cam.

An additional object of our invention is the provision of an apparatus of the aforementioned type in which the aforesaid carriage has secured thereto punch means adapted to preform fastener receiving holes in a base strip when said carriage moves from its first, uppermost position to its second, lowermost position.

Another object of our invention is the provision of an apparatus of the aforementioned type in which said punch means has its longitudinal axes vertically oriented so that vertical fastener receiving holes will be formed in the angularly disposed base strips by said punch means.

A further object of our invention is the provision of an apparatus of the aforementioned type in which release means is operatively connected to said punch means to permit the voluntary inactivation of said punch means so that, when a base strip through which fasteners have not been driven is rerun through the apparatus, the punch means will be rendered inoperative and not form additional openings or holes in the base strip.

A further object of our invention is the provision of an apparatus of the aforementioned type which includes fastener driving means for inserting fasteners in fastener receiving holes previously formed in the base strip by the aforementioned punch means. An associated object of our invention is the vertical orientation of the fastener driving means on the carriage of the apparatus so that the fasteners will be driven into the base strip with their longitudinal axes vertically aligned.

Although the material utilized in the base strips of the carpet fasteners is characterized by extremely high anti-splitting characteristics, it has been discovered that the force with which the fasteners are driven through the base strips, despite the previous formation therein of fastener receiving holes, will cause the splintering of the base strips to such an extent as to render the completed carpet fastener less salable. It was necessary, therefore, to provide an anti-splintering means which would prevent the splintering of the base strips while the fasteners were driven thereto by the fastener driving means.

Another object of our invention is the provision of temporary support means for the base strips which substantially encompass the preformed holes therein and which temporarily support the face of the strip adjacent said holes when the fasteners are driven therethrough.

An additional object of our invention is the provision of an apparatus of the aforementioned type in which the aforesaid temporary support means is provided with a plurality of receptacles for receiving the portions of the fasteners extending from the upper face of said strip after they have been driven therethrough and which is so designed that, when the base strip is translated along the bed of the apparatus after the driving of the fasteners therethrough, the fasteners cause the rotation of the temporary support means to juxtapose another receptacle in the temporary support means below the next fastener receiving hole.

It is extremely important that the lengths of the portions of the fasteners which project above the face of the base strip be substantially uniform and maintained at optimum lengths. This is due to the fact that the edge of a carpet at-

tached to the fasteners of the carpet fastener must be simultaneously impaled upon a relatively large number of the fasteners and, if the lengths of the portions of the fasteners projecting above the face of the base strip were not substantially equal, difficulty in securing the edge of a rug or carpet thereto would be encountered. Furthermore, if the protruding portions of the fasteners were too short, insufficient hooking action of the fasteners would cause the carpet to tear upon the application of tension used in installing the carpet. If the protruding portions of the fasteners were too long, they would penetrate the upper surface of the carpet.

Another object of our invention is the provision of an apparatus of the aforementioned character which includes fastener depth adjusting means for insuring that the lengths of the portions of the fasteners projecting beyond the face of the base strips are substantially uniform and maintained at an optimum length.

Other objects and advantages of our invention will be apparent from the following specification and the accompanying drawings, which are for the purpose of illustration only, and in which:

Fig. 16 is an enlarged view of the prepunch of the invention.

Referring to the drawings, and particularly to Fig. 1 thereof, we show a carpet fastener manufacturing apparatus 10 constructed in accordance with our invention and including a frame 11, said frame being constituted, in part, by an elongated table structure 12 and a pair of vertical standards 14 and 15 disposed rearwardly of the table structure 12 and spaced laterally from each other. Mounted on the vertical standards 14 and 15 and reciprocable between a first, uppermost posi-

tion and a second, lowermost position, is a carriage 17. Supported upon the table structure 12 is a bed structure 19, said bed structure being shown generally in Fig. 2 of the drawings and being designed to receive a carpet fastener base strip 21 such as that of the completed carpet fastener 22 shown in Fig. 14 of the drawings.

Considering the nature and construction of the carpet fastener 22 which is manufactured in the apparatus 10, said fastener includes the base strip 21 which is formed of wood or similar material and which is provided with a plurality of elongated fasteners 23 which project upwardly and angularly from the upper face 24 of the base strip 21. It should be understood that, when the base strips 21 are fed into the apparatus 10, the upper faces thereof are disposed downwardly so that the fasteners can be driven therethrough in a manner to cause them to project from and above said upper faces.

Disposed adjacent the receiving end of the bed structure 19, that is, the right-hand end of the bed structure as shown in Fig. 2 of the drawings, is a base strip receiving bin 26 for receiving a large number of base strips 21 to supply said strips to the receiving end of the bed structure 19, in a manner which will be described in greater detail below. The base strip receiving bin 26, as best shown in Figs. 2, 4 and 5 of the drawings, includes an elongated bottom portion 28, said bottom portion being constituted by an elongated channel 29 of substantially L-shaped configuration. It will be noted, as best shown in Fig. 4 of the drawings, that the bottom leg 31 of the L-shaped channel 29 is inclined approximately 30° from the horizontal while the side leg 32 of the L-shaped channel 29 is inclined approximately 30° from the vertical.

The outermost end of the L-shaped channel 29 is supported upon a vertical standard 34, while the delivery end thereof is affixed to the receiving end of a portion of the bed structure 19 by means of a mounting plate 35 which has one leg 36 secured by a bolt 37 to the receiving end of the bed structure 19 and its other leg 38 welded to the delivery end of the L-shaped channel 29.

Adjustably secured to the L-shaped channel 29 adjacent the outermost end thereof is an outermost bin end 40, best shown in Figs. 2 and 15 of the drawings, and including an angularly oriented retainer 42 having its lowermost end 43 seated on the bottom leg 31 of the L-shaped channel 29 and its side wall 44 maintained in contiguity with the side leg 32 of the L-shaped channel 29. The end wall 45 of the angularly oriented retainer 42 engages the outermost ends of base strips 21 deposited in the bin 26, as best shown in Fig. 2 of the drawings, and serves to retain said strips in said bin. A reinforcing plate 46 appropriately secured, as by welding, to the back of the side wall 44 of the retainer 42 has its lowermost end engaging the top of the side leg 32 of the L-shaped channel 29, a retainer block 48 being provided on the lowermost end of the reinforcing plate 46 which engages the upper portion of the side leg 32 of the L-shaped channel 29 to prevent the angularly oriented retainer 42 from being laterally displaced from the channel 29.

Fastened to the reinforcing plate 46 of the angularly oriented retainer 42 by means of a connecting arm 49 is an adjustment means 50 for adjustably positioning the angularly oriented retainer 42 at a desired point along the length of the L-shaped channel 29 to permit base strips

21 having different lengths to be accommodated in the base strip receiving bin 26. The adjustment means 50, shown in detail in Fig. 15 of the drawings, includes an elongated slide bar 52 which engages the outer surface of the side leg 32 of the L-shaped channel 29 and has fastened thereto, as by means of welding, a securing clip 53 the upper end of which is fastened to the slide bar 52 and the lower end of which underlies the bottom leg 31 of the L-shaped channel 29. A bolt 54 threaded in the securing clip 53 has its end positioned to engage the intersection of the bottom leg and side leg 31 and 32 of the L-shaped channel 29 to secure the adjusting means 50 and, therefore, the angularly oriented retainer 42 against movement with respect to the L-shaped channel 29.

If it is desired to shift the angularly oriented retainer 42 along the length of the channel 29 to increase or decrease the size of the base strip receiving bin 26, the bolt 54 is unscrewed in the securing clip 53 to release it from engagement with the L-shaped channel 29, thus permitting the sliding bar 52 and the retainer block 48 to be slid along the side leg 32 of the L-shaped channel 29. When the desired point of adjustment of the angularly oriented retainer 42 is reached, the bolt 54 is threaded into the securing clip 53 to cause the end of the bolt to engage the interior of the L-shaped channel 29 and hold the adjustment means 50 and the associated angularly oriented retainer 42 against inadvertent movement along the L-shaped channel 29.

Fastened to the side leg 32 of the L-shaped channel 29 intermediate its outermost and delivery ends are guide rails such as the guide rail 56 adapted to prevent the inadvertent, lateral dislocation of the base strips 21 deposited in the bin 26 therefrom. It should be noted that the guide rails 56, the angularly oriented retainer 42 and the L-shaped channel 29 are angularly positioned to position base strips 21 deposited therein so that, when the fasteners 23 are driven into the base strip 21, they will project from the upper face 24 thereof at an angle thereto.

Positioned at the delivery end of the base strip receiving bin 26, as best shown in Figs. 2, 4, and 5, is a delivery gate 58, said gate being constituted, in part, by a substantially L-shaped shield 59, the lower end of the side wall 60 of which is secured to the leg 38 of the mounting plate 35 by means of welding or appropriate fasteners to orient the shield 59 with respect to the L-shaped channel 29. Thus, the side wall 60 is maintained at substantially the same angle to the horizontal as is the side leg 32 of the L-shaped channel 29 and is adapted to prevent the lateral dislocation of base strips 21 from the bin 26. The front wall 62 of the shield 59 has its lowermost end terminating a substantial distance above the bottom leg 31 of the channel 29 to provide a delivery opening 64, best shown in Fig. 4 of the drawings, through which the forward end of the lowermost base strip 21 in the bin 26 is drawn, as will be described in greater detail below.

Provided on the front wall 62 of the shield 59 is an adjustable tongue 66, said tongue being slidably mounted in a slider block 67, the tongue 66 and the slider block 67 being mounted on the front wall 62 by means of a bolt 68 which can be released to permit the lowermost end of the tongue to be raised and lowered across the delivery opening 64 at the lower end of the front wall 62 of the shield 59 and which can be then

tightened to maintain the adjustable tongue 66 in a predetermined position.

It should be noted at this juncture that the end wall 45 of the angularly oriented retainer 42 and the front wall 62 of the shield 59 are rearwardly inclined with respect to the vertical and have their longitudinal axes arranged in substantial, but not exact, parallelism with each other. The angularly oriented retainer 42 is always adjusted on the channel 29 by means of the adjustment means 50 so that the longitudinal distance between the inside of the front wall 62 of the shield 59 and the inside of the rear wall 45 of the angularly oriented retainer 42 is always substantially less than the contemplated lengths of the base strips 21 which are to be deposited therein, thus causing the base strips 21 to have their longitudinal axes angularly oriented with respect to a horizontal plane so that the forward ends thereof abut against the inside of the forward wall 62 of the shield 59 and are positioned substantially lower than the rearward ends thereof which abut against the rear wall 45 of the angularly oriented retainer 42. This is an extremely important feature of the apparatus of our invention and the method by which the carpet fasteners are manufactured since it prevents the entire weight of a stack of superimposed base strips 21 from being imposed upon the lowermost of the base strips which is being withdrawn from the bin 26 and conveyed across the bed structure 19, in a manner to be described below. As can be most clearly seen from Fig. 2 of the drawings, when a base strip 21 has been drawn through the opening defined by the lowermost end of the tongue 66 projecting into the opening 64, only the extreme forward end of the adjacent, superimposed base strip 21 rests thereupon, permitting the base strip 21 being acted upon by the apparatus 10 to be withdrawn from the bin with relative ease since the entire load of the base strips 21 in the bin 26 is not supported thereupon but is partially supported between the end wall 45 of the angularly oriented retainer 42 and the forward wall 62 of the shield 59.

The primary function of the adjustable tongue 66 is to vary the size of the opening 64 so that base strips 21 of varying thicknesses may be drawn through the opening 64. Therefore, when it is desired to change the thickness of the base strips 21 being operated upon by the apparatus 10, the tongue 66 is merely adjusted with reference to the opening 64 by means of the loosening of the bolt 68 to permit it to be adjusted to the proper height with respect to the opening 64.

Considering the mode of actuation and construction of the carriage 17 in greater detail, particular reference being had to Figs. 1 and 2 of the drawings, the vertical standards 14 and 15 are provided with vertical grooves 10 on the interior faces thereof, said grooves being designed to receive vertical slider members 71 of the carriage 17. A transverse cross-arm 74 spans the space between the vertical sliders 71 on the carriage 17 and is secured thereto by means of bolts 75, or similar fasteners, adjacent the lower ends thereof. A clevis 76 is formed integrally with the cross-arm 74 and located intermediate the ends thereof and is connected to the upper end of a connecting rod 78 by means of a wrist pin 77, the lower end of said connecting rod being secured to a crank 79 on a shaft 80 which is connected to a power source, not shown.

Carried on the cross-arm 74 is a drive bar 82, said drive bar being carried up and down by the

movement of the cross-arm 74 as caused by the vertical movement of the connecting rod 78 between a first, uppermost position and a second, lowermost position for purposes which will be described in greater detail below. Disposed below the drive bar 82 of the carriage 17 and fixedly secured between the vertical standards 14 and 15 is a mounting bar 84, which is provided with a longitudinal mounting slot 85.

Secured to the drive bar 82 of the carriage 17 at the right-hand end thereof, as viewed in Figs. 1 and 2 of the drawings, is an elongated cam member 87, said cam member having formed upon the lowermost end thereof a cam 88 having a rise portion 89 and a dwell portion 90. The cam member 87 is provided with auxiliary support by means of a roller 91 secured in a recess in one end of the fixed mounting bar 84. Therefore, as the carriage 17 is moved up and down on the standards 14 and 15 by the action of the connecting rod 78, the cam member 87 is simultaneously reciprocated with the carriage 17, for purposes which will be described in greater detail below.

Also carried on the drive bar 82, as best shown in Figs. 2, 7, 8, 10, and 13, are the punch means 92, the fastener driving means 93 and a portion of the depth adjustment means 95 of the apparatus 10. The punch means 92 and the fastener driving means 93 are arranged in spaced sets, that is, sets consisting of one punch means 92 and one fastener driving means 93, as best shown in Figs. 2 and 13 of the drawings. The first set of punch and fastener driving means is positioned inwardly from the second set, as best shown in Fig. 13, so that the punch means 92 of the first set pre-punches the holes of a first row 97 of fasteners 23 of the carpet fastener 22 while its associated fastener driving means 93 drives the fasteners in said first row, the second set of punch means 92 and fastener driving means 93 being spaced outwardly from the first set to pre-punch the holes in the carpet fastener 22 and drive the fasteners in a second row 98 of fasteners 23. Therefore, the second row 98 of fasteners 23 is inserted in the base strip 21 subsequently to the insertion of the first row of fasteners therein as will be apparent from a further consideration of the specification.

Since both of the punch means 92 are identical in configuration and construction and differ merely in their mounting place on the drive bar 82, only one of the punch means will be described. As previously indicated, it has been discovered that it is desirable to pre-punch holes in the base strips 21 prior to driving the fasteners 23 therethrough. In performing this pre-punching operation, the punch means 92 of the first set of punch and fastener driving means punches the first row 97 of holes in the base strip 21 while the punch means 92 of the second set of punch and fastener driving means punches the holes of the second row 98 in the base strip 21.

The punch means 92, as best shown in Figs. 2 and 7 of the drawings, includes a mounting shank 103 positioned in a vertical bore 104 in the drive bar 82 and secured therein by means of a nut 105 fastened to the upper end of the shank. The vertical bore 104 is provided with a counterbore 106 at its lowermost end, said counterbore being designed to receive the upper portion of a mounting block 107, the upper end of said mounting block being normally disposed adjacent the entrance of said counterbore and spaced below the shoulder 109 provided by the counterbore 106.

at its upper end. A punch receiving socket 110 has a threaded upper portion 111 which engages the lowermost end of a nut portion 112 provided on the lowermost end of the mounting block 107. Secured in the socket 110, as by means of a set screw 114, is the upper end of an elongated punch 115. A guide block 117 is fixedly secured to the mounting bar 84 through the medium of the mounting slot 35 and a bolt 118 and provides an elongated, vertical bore 120 which is designed to guide the hole forming end 122 of the punch 115. The punch means 92 shown in Fig. 7 of the drawings is included in the second set of punch and fastener driving means and, consequently, is designed to form the holes for the reception of the second row 98 of fasteners 23.

The forming end 122 of the punch 115 is shown in greater detail in Fig. 16 of the drawings and includes a shoulder 280 which provides a seat for the head of a fastener 23 and a pin 281 for forming a hole for guiding the fastener shank through the base strip 21. Thus the punch 115 forms a hole for both guiding the fastener 23 and reducing the force necessary for driving same. The shoulder insures that the seat for the head of the fastener 23 will not be driven too deeply into the base strip 21.

Mounted on the top of the drive bar 82 and overlying the retaining nuts 105 and upper ends of the shanks 103 of the punch means 92 is a punch release means 125 constituted by an elongated lever 126 which is pivotally mounted for rotation in a horizontal plane by means of a pivot 127, as best shown in Figs. 2, 7, and 13 of the drawings. When the release means 125 is in the full-line position shown in Fig. 13 of the drawings, the upper ends of the mounting shanks 103 of the punch means 92 are retained by the release lever 126 against movement in the bores 104 in the drive bar 82 when the carriage 17 is moved downwardly to carry the punch means 92 downwardly and into a base strip 21 deposited therebelow.

However, after a base strip 21 of a carpet fastener 22 has been run through the apparatus 10, it is occasionally discovered that certain of the pre-punched holes have not had fasteners 23 driven therethrough, necessitating the passage of the imperfect carpet fastener 22 through the apparatus 10 for a second time. To prevent the undesired impingement of the hole forming ends 122 of the punch means 92 on fasteners 23 which have already been driven into base strips 21, the lever 126 of the release means 125 is rotated on the pivot 127 into the dotted line position shown in Fig. 13 of the drawings. When so disposed, the lever 126 is moved out of alignment with the upper ends of the mounting shanks 103 of the punch means 92 and, when the hole forming ends 122 of the punch means 92 impinge upon the tops of fasteners 23 already driven into the base strip 21, the mounting blocks 107 are moved upwardly in the counterbores 106 at the lower ends of the bores 104 until the upper ends thereof impinge on the shoulders 109 at the upper ends of said counterbore. In this manner, damage to the hole forming ends 122 of the punches 115 is prevented and, when the defective carpet fastener 22 has been run through the apparatus 10, the lever 126 of the release means 125 can be rotated to the full line position shown in Fig. 13 of the drawings to restrain the upper ends of the mounting shanks 103 and thus the punch means 92 from the upward movement in the bores 104 and their associated counterbore 106.

The manner in which the hole forming end 122 of the punch 115 is driven into a base strip 21 is graphically illustrated in Fig. 7 of the drawings, it being clearly shown that the hole forming end 122 of the punch 115 does not fully penetrate the base strip 21 but provides a hole for receiving a fastener 23 which is subsequently driven thereinto and completely through the base strip 21 in a manner to be described in greater detail below. In considering Fig. 7 of the drawings, it should be noted that the bed structure 19 includes a centrally located segment 130, said segment being provided with a front wall 131, a rear wall 132 and a base 133, all of which are fastened by suitable fastening means, such as welding, to the table structure 12. Supported upon the upper edges of the front and rear walls 131 and 132 and disposed at an angle of substantially 30° with the horizontal surface of the table structure 12 is a bed plate 134 which is provided with a pair of elongated grooves 135 and 136, said grooves being designed to permit the passage of the fasteners 23 after they have been inserted in the base strip 21. It will be noted that the grooves 135 and 136 are vertically oriented as are the punches 115 of the punch means 92 so that the pre-punched holes formed in the base strip 21 are vertically oriented but angularly inclined with respect to the upper face of the base strip 21.

It should also be noted that the angular inclination of the bed plate 134 with respect to the horizontal is substantially equal to the angle of inclination of the base strip receiving bin 26 so that the angular orientation of the transverse axes of the base strips as they pass along the bed structure 19 from the bin 26 is preserved to accomplish the angular orientation of the fasteners 23 driven into the base strip.

If it is desired to increase or reduce the depth of the holes formed by the punch 115, the threaded portion 111 of the socket 110 can be rotated in the nut 112 on the mounting block 107 to cause a corresponding extension or retraction of the threaded portion 111 from or into the nut 112, thus reducing or increasing the distance between the lower end of the punch 115 and the base strip 21 when the drive bar 82 of the carriage 17 is in its first, uppermost position. Therefore, when different gages of base strip material are utilized, the lower end of the punch 115 can be raised or lowered by the aforementioned adjustment of the threaded portion 111 of the socket 110 to permit the depth of penetration of the punch 115 in the base strip 21 to be adjusted.

Since the fastener driving means 93 of the first and second sets of punch and driving means are identical in configuration, only the fastener driving means 93 of the second set will be described, it being understood that the construction of the fastener driving means 93 of the first set is identical therewith with the exception of the fact that fastener driving means 93 of the first set is designed to drive the fasteners 23 of the first row 97 while the fastener driving means 93 of the second set is designed to drive the fasteners 23 of the second row 98 of fasteners in the base strip 21 of the carpet fastener 22.

The fastener driving means 93 includes a mounting shank 138, as best shown in Figs. 2, 8, and 13 of the drawings, said mounting shank being secured by means of a nut 139 in a vertical bore 140, said bore being provided at its lower end with a counterbore 141 against the upper

end of which is seated a mounting block 142 which has an adjustment nut 143 secured to the lower end thereof. A socket 144 has its threaded upper end 145 secured in the mounting block 142 and is designed to receive the upper end of a fastener driving rod 147. The lower end of the driving rod 147 is disposed in a vertical bore 149 in a guide block 150 which is fastened to the mounting bar 84 by means of a bolt 151. The threaded upper end 145 of the socket 144 can be retracted into or extended from the nut 143 on the lower end of the mounting block 142 to cause the spacing of the lower end of the fastener driving rod 147 above the bed plate 134 to be correspondingly increased or decreased.

Mounted on the guide block 150 is a pair of fastener feeding jaws 153 the lowermost ends of which are disposed below the end of the vertical bore 149. A fastener feeding passage 155 in the guide block 150 communicates with the vertical bore 149 and receives fasteners 23 from a feeder, not shown, through a tube 156, the fasteners being fed from the feeding passage 155 into the jaws 153 from which they are expelled by the downward movement of the fastener driving rod 147 which movement drives them through the holes previously formed in the base strip 21, as best shown in Fig. 8 of the drawings. Thus, after a hole has been pre-punched in the base strip 21 by either the punch means 92 of the first set or the punch means 92 of the second set, its associated fastener driving means 93 drives a fastener 23 into the hole and causes a substantial portion thereof to be projected from the upper face of the base strip 21 which is inverted on the bed plate 134 of the centrally located segment 130 of the bed structure 19.

Therefore, when the carriage 17 is reciprocated from the first, uppermost position to the second, lowermost position, two fasteners 23 are simultaneously driven through the base strip 21 in the first and second rows 97 and 98 by means of the fastener driving means 93 while two holes are simultaneously pre-punched adjacent to, but spaced from, the holes in which the fasteners 23 are driven simultaneously with the driving of the same by means of the punch means 92 associated with said fastener driving means 93.

As previously indicated, we have discovered that even when the holes for receiving the fasteners 23 are pre-punched in the base strip 21, splintering of the material on the inverted upper face of the base strip will occur when the fasteners 23 are driven into the pre-punched holes by the action of the fastener driving means 93 of the apparatus 10. Since the splintering of the base strip 21 materially reduces the marketability thereof, we have provided anti-splintering means constituted by auxiliary support means 160 and 161, best shown in Fig. 11, which are respectively disposed in recesses 162 and 163 in the bed plate 134 of the centrally located bed structure segment 130. The auxiliary support means 160 and 161 are respectively embodied in starwheels 164 and 165 mounted for rotation on pins 166 and 167, said pins being secured by appropriate means to the bed plate 134. Since the auxiliary support means 160 and 161 are identical in configuration, structure, and mode of operation, only the wheel 164 will be described, identical numerals being applied to the wheel 165. The starwheel 164 is provided with a plurality of lobes 170 which define therebetween fastener receiving spaces 171. When a portion of a fastener is driven into the base strip 21 by the action of the fastener driving means 93

93, it is projected through the space which completely spans the groove 135, that is, the space 171a in Fig. 11 of the drawings. In a similar manner, the space 171a between the lobes 170 of the starwheel 165 which overlies and spans the groove 136 in the bed plate 134 is designed to receive a fastener projected therethrough by the fastener driving means 93 of the second set. It will be noted that the spaces 171 between the lobes 170 of the starwheel 164 are of relatively small width so that the edges of adjacent lobes 170 support the inverted base strip 21 adjacent the pre-punched openings when the fasteners 23 are driven therethrough. The additional support provided by the edges of the lobes 170 of the starwheel 164 prevents the splintering, distortion, or configuration of the face of the base strip 21 and also serves to support the area contiguous to the undersides of the pre-punched holes when the fasteners 23 are driven therethrough.

Associated with the starwheels 164 and 165 are registering means 173 consisting of elongated spring strips 174 having detent pins 175 secured to one end thereof while their opposite ends are mounted in mounting blocks 176 secured adjacent the edges of the bed plate 134. The detent pins 175 are shaped to fit between the outer ends of adjacent lobes 170 of the starwheels 164 and 165 and are designed to restrain the starwheels 164, 30 165 against inadvertent rotation so that the spaces 171a lying across the grooves 135 and 136 will register during a period in which a fastener is driven with the lower ends of the fastener driving means 93 so that there will be no possibility 35 that a fastener will be driven into one of the lobes 170 rather than therebetween.

After a fastener 23 has been driven through the base strip 21, the strip is translated along the bed plate 134 by means to be described in detail hereinafter and the projecting portion of the fastener located in the opening 171a causes the rotation of the starwheel 164 in a clockwise direction, said rotation urging the pin 175 out of the space 171 in which it has previously rested and permitting a new space 171 to be positioned across the groove 135 and to span the same. When the starwheel 164 is so rotated, the fastener 23 leaves the wheel before the complete rotation of the wheel is accomplished but the radius on the lobe of the wheel is engaged by the pin 175 whose spring bias causes the additional rotation of the wheel into proper position. When the space 171 is properly positioned, the detent pin 175 enters a new space and the starwheel 164 is held against inadvertent rotation. In this manner, the projecting portions of the fasteners driven into the spaces 171 between the lobes of the starwheels 164 and 165 also accomplish the rotation thereof to bring successive spaces 171 between the lobes 170 into registry with the grooves 135 and 136 with which they are associated.

The depth adjustment means 95 of the apparatus 10 includes hammer means 180 mounted on the drive bar 82 of the carriage, said hammer means including, as best shown in Fig. 10 of the drawings, a cylinder 181 affixed to the drive bar 82 by means of a bolt and nut combination 183. The cylinder 181 provides a vertical bore 184 in which is disposed the upper end of a reciprocable rod 185. Fastened to the lowermost end of the rod 185 is a hammer 186 which has an angularly oriented striking face 187. The angular orientation of the striking face 187 is approximately 30° from the horizontal and corresponds to the an-

gular orientation of the bed plate 134 and the base strip 21 deposited thereupon. A compression spring 189 encompasses the lower end of the reciprocable rod 185 and has its upper and lower ends seated respectively against the lower end of the cylinder 181 and the upper end of the hammer 186.

Disposed below the hammer means 180 of the depth adjustment means 95 is the anvil means 191 thereof, said anvil means including a first anvil 192 and a second anvil 193, the upper ends of which project respectively into the grooves 135 and 136 of the bed plate 134 through openings in said plate and are designed to be engaged by the lowermost ends of fasteners 23 which have been driven through the base strip 21, as best shown in Fig. 10 of the drawings. The tops of the anvils 192 and 193 are frusto-conical to permit fasteners which protrude excessively to ride up on the anvils and to prevent their being caught on the edges thereof. The lowermost ends of the anvils 192 and 193 are threaded in a mounting block 195, said anvils being designed to be extended into and retracted from the openings in the bed plate 134 by means of heads 196 provided thereupon.

It will be noted that the anvils 192 and 193 are spaced so that the anvil 192 cooperates with the groove 135 and the anvil 193 cooperates with the groove 136 so that the anvil 192 adjusts the depth of the fasteners 23 in the first row 97 while the anvil 193 adjusts the fasteners 23 of the second row 98. The tops of the anvils 192 and 193 are also staggered longitudinally with respect to each other so that the depth of penetration of the fasteners 23 in the base strip 21 in the adjacent rows of fasteners may be simultaneously adjusted.

After the fasteners 23 have been driven through the base strip 21 by the action of the fastener driving means 93, the strip 21 is moved along the bed plate 134 so that the fasteners 23 just previously driven are halted momentarily under the hammer 186 of the hammer means 180. The hammer 186 is carried downwardly with the descent of the drive bar 82 causing the angularly oriented face 187 thereof to impinge upon the base strip 21 and force it against the bed plate 134. Therefore, if the fasteners 23 have been driven too deeply through the base strip 21, the action of the hammer 186 will force the lowermost ends of the fasteners against the upper ends of the anvils 192 and 193 to cause the fasteners 23 to be urged upwardly until the lengths of the portions projecting from the base strip 21 equal the desired length. Therefore, it is possible to maintain the extent of projection of the fasteners from the face of the strip 21 substantially uniform so that no difficulty is encountered in affixing the edge of the carpet thereto. Furthermore, the adjustability of the anvils 192 and 193 permits the extent of projection of the fasteners above the face of the base strip 21 to be regulated in accordance with the thickness of the strip, the length of the fasteners, and other factors. It will also be noted that the fact that the hammer 186 is spring biased permits a sufficient, but not excessive, pressure to be applied to the base strip 21 so that no injury or distortion of the base strip will occur.

Conveyor means 200 is provided on the apparatus 10 to convey the base strip 21 along the bed structure 19 and particularly along the centrally located segment 130 of the bed structure so that the various operations involved in the

formation of the carpet fastener 22 may be performed upon the base strip 21. The conveyor means 200, as best shown in Figs. 1, 2, and 3-6 of the drawings, includes a longitudinally reciprocable conveyor carriage 202 which is slidably mounted on a wedge block 203 secured to the table structure 12 by means of bolts 204. A longitudinally oriented guide rod 205 is secured in the body of the conveyor carriage 202 and has its opposite end slidably mounted in an aperture 207 in the end of the wedge block 203. A compression spring 208 encompasses the guide rod 205 and has one end seated against the carriage 202 while its other end is seated on a spring seat 209 adjacent the aperture 207 in the wedge block 203. A pair of nuts 211, Fig. 6, is threaded onto the end of the guide rod 205 projecting through the aperture 207 to retain the free end of the guide rod 205 against ejection from the aperture 207 by the biasing action of the spring 208, said spring tending to urge the guide rod 205 and the conveyor carriage 202 associated therewith in a direction away from the aperture 207, that is, a direction to the left as shown in Figs. 1, 2, and 6 of the drawings.

Mounted on the left-hand end of the conveyor carriage 202 is cam follower means 215, said means being constituted by a roller 216 revolvably mounted on a pin 217 secured in the upper end 30 of a standard 218 which is formed integrally with the left-hand end of the conveyor carriage 202. The roller 216 of the cam follower means 215 is urged into engagement with the rise portion 89 of the cam member 88 because the spring 208 carries the carriage 202 to the left and serves to maintain the roller 216 in continuous engagement with the cam 88.

Therefore, when the carriage 17 descends and the cam 88 is carried downwardly therewith, the roller 216 rides on the rise portion 89 of the cam 88 as the rise portion descends, being urged to the right against the bias of the spring 208 and gradually compressing same, as the guide rod 205 is projected from the aperture 207 in the wedge block 203. When the roller 216 reaches the crest of the rise portion 89 of the cam 88, it enters the dwell portion 90 of the cam and is held immobile in an extreme right-hand position. Subsequently, when the carriage returns from its second, lowermost position to its first, uppermost position, the roller 216 rides down the dwell portion 90 of the cam 88 to the rise portion 89 thereof and the spring 208 shifts the carriage 202 to the left. It is apparent, therefore, that during a substantial portion of the movement of the carriage 17 into its second, lowermost position, the carriage 202 is held by the dwell portion 90 of the cam 88 against movement in its extreme right-hand position thus immobilizing temporarily the base strip 21 being conveyed by the conveyor means 200, in a manner to be described in greater detail below, and rendering the conveyor means 200 intermittent in operation.

Mounted on the conveyor carriage 202 and longitudinally reciprocable with said carriage is an auxiliary bed segment 220 which has securely attached thereto a longitudinally reciprocable retainer bar 221. Fastened at one end to the auxiliary bed segment 220, which is oriented at an angle of substantially 30° to the horizontal, is a connector bar 223 which is also oriented at an angle of 30° to the horizontal and which provides an auxiliary supporting surface for the upper edge of the base strip 21 as it is conveyed through the apparatus 10. The connector bar 223 is pro-

vided intermediate its ends with an integral offset portion 224 constituted by an upraised bump which clears the starwheel 164 and other portions of the mechanism.

Formed integrally with or otherwise suitably connected to the opposite end of the connector bar 223 is a second auxiliary bed segment 226 having appropriately located grooves 227 and 228 which register, respectively, with the grooves 135 and 136 in the centrally located bed segment 130 to permit the passage of fasteners 23 after they have been driven through the base strip 21. A longitudinally reciprocable retainer bar 230 is secured to the second auxiliary bed segment 226 and, as best shown in Figs. 1 and 2-3 of the drawings, is slidably supported on a standard 232 at one end of the bed structure 19, said standard being provided at its upper end with rollers 234 and 235 which respectively engage the lower edge and the underside of the guide bar 230 and thus support the second auxiliary bed segment 226 and the outermost end of the connector bar 223.

Rotatably secured to the connector bar 223 at its right-hand end, as viewed in Fig. 1 of the drawings, is a spring biased pawl 238 which is biased by a spring 239 into a position in which its lowermost end engages the edge of a base strip 21, a similar pawl 241 being located at the opposite end of the connector bar 223 and being biased in a similar manner by means of a spring 242.

A connector rod 244, as best shown in Figs. 2 and 5 of the drawings, turns the pawls 238 and 241 so that the engagement and release of the lowermost ends thereof with or from the upper edge of a base strip 21 or a plurality of base strips 21 occurs simultaneously.

The operation of the conveyor means 200 is as follows: When the descent of the cam 88 on the carriage 17 causes the movement of the conveyor carriage 202 to the right, as viewed in Figs. 1 and 2 of the drawings, the lowermost end of the pawl 238 is caused to ride freely over the upper edge of the lowermost base strip of a stack of superimposed base strips 21 in the bin 26 adjacent the delivery end thereof. During the momentary halt in the reciprocable movement of the conveyor means 200, occasioned by the engagement of the cam follower roller 216 with the dwell portion 90 of the cam 88, no movement of the base strips 21 from the bin occurs. However, when the carriage 17 starts its movement from the second, lowermost position to the first, uppermost position and the cam follower roller 216 reaches the rise portion 89 of the cam 88, the conveyor carriage 202 begins to move to the left, as viewed in Figs. 1 and 2 of the drawings, because of the bias of the spring 238 associated therewith. Simultaneously, the lowermost end of the pawl 238 bites into the upper edge of the base strip 21 and draws it through the delivery opening 64 of the bin 26. In setting up the apparatus for operation, it is customary to manually place a base strip 21 on the centrally located bed segment 130 in a position where the punch means 92 and the fastener driving means 93 may initiate their operations on the strip without the necessity for waiting for the apparatus to deliver a strip thereto.

However, during the subsequent operation of the machine, the base strips 21 are moved through the apparatus 10 by the action of the conveyor means 200 alone. It should be noted that the movement of the conveyor carriage 202 to the left by the action of the spring 238 impales the base strips 21 upon the lowermost ends of the

pawls 238 and 241 and causes an increment of movement in the base strips 21 which is equal to the distance between adjacent fasteners 23 in the rows of fasteners.

As the carriage 17 is reciprocated between the first, uppermost position and the second, lowermost position, the conveyor carriage 202 is shifted back and forth from left to right and from right to left, as shown in Figs. 1 and 2 of the drawings, the movement of the conveyor carriage 202 to the right being accomplished by the downward movement of the carriage 17 and the movement of the conveyor carriage 202 to the left being permitted by the upward movement of the carriage 17. In this manner, the base strip 21 is carried along the centrally located bed segment 130, the descent of the carriage 17 into the second, lowermost position causing six operations to take place simultaneously, that is, two holes are pre-punched in the base strip 21 by the punch means 92, two fasteners are driven into holes previously formed by the punch means 92 by the fastener driving means 93 and two driven fasteners have the lengths of their projecting portions adjusted by the depth adjustment means 95.

When the end of a completed carpet fastener 22 passes from the end of the centrally located bed segment 130, the pawl 241 of the conveyor means 200 continues to move the completed carpet fastener 22 along the bed structure 19 until it is discharged therefrom. It will be noted that a fixed guide bar 250, best shown in Fig. 2 of the drawings, is provided between the reciprocable retainer and guide bars 221 and 230, said fixed guide bar being securely fastened to the centrally located bed segment 130 adjacent its ends. Secured to the right-hand end of the fixed guide bar 250 is a retainer block 253 which is adjustably mounted on and overlies the base strip 21 as it is drawn from the bin 26 and prevents the base strip 21 from being dislodged from the bed structure 19. The adjustable mounting permits strips of various thicknesses to be accommodated.

The method of our invention is defined by the steps of angularly orienting a base strip to permit vertical openings to be formed therein which will subsequently have driven therethrough fasteners 23 whose projecting ends are angularly oriented with respect to the face of the base strip 21. Also included in the steps comprising the method of our invention is the idea of providing temporary auxiliary support for the inverted face of the base strip 21 while the fasteners are driven into the pre-punched holes therein, said auxiliary support preventing the splintering or excessive disfiguration of the face of the strip and increasing the marketability thereof. Another step comprised in the practice of the method of our invention is the automatic depth adjustment of the projecting portions of the fasteners 23 previously driven through the base strip 21 by the action of the fastener driving means 93 to insure the equal and uniform projection of the ends of the fasteners above the face of the base strip 21.

Another aspect of the practice of the method of our invention is the superimposition of the base strips 21 in the bin 26 in such a manner that both the longitudinal and transverse axes are angularly oriented with respect to a horizontal plane. Thus, the lowermost of the superimposed pile of base strips 21 in the bin 26 will, when drawn from the delivery end of the bin through the delivery opening 64, be engaged by only the lowermost

end of the next succeeding base strip 21 so that there is a minimal resistance to the withdrawing of the base strip from the bin by the action of the conveyor means 200.

Among the important contributions to the art included in the apparatus 10 of our invention is the provision of the adjustable bin 26 for receiving the base strips 21, the intermittent conveyor means 200 for moving the base strips 21 along the bed structure by increments which are equal to the spaces between adjacent fasteners, the provision for simultaneously preforming fastener receiving holes in the base strip and for driving fasteners in previously formed holes, the temporary auxiliary supporting means which permits the face of the base strip to be supported close to the previously formed holes in the base strip to prevent the splintering or excessive disfiguration of the face when the fasteners are driven therethrough, and the release means incorporated in the apparatus for permitting the punch means 92 to be temporarily inactivated when an imperfectly manufactured fastener 22 is refed through the apparatus or backed up manually.

Also of importance is the automatic depth adjusting means for adjusting the lengths of the projecting portions of the fasteners to a predetermined norm and various other features of the apparatus 10 which are not specifically alluded hereto but which appear in the specification and the accompanying drawings.

We claim as our invention:

1. In an apparatus for inserting fasteners in a base, the combination of: a bed for receiving said base; a conveyor for moving said base along said bed; punch means for forming fastener receiving holes in said base; support means on said bed for engaging and supporting the underside of said base adjacent said holes during the driving of said fasteners therethrough, said support means being fixedly secured intermediate the ends of said bed and being movable on said bed about its point of securement thereto; and fastener driving means for inserting said fasteners in said holes and driving them through said base.

2. In an apparatus for inserting fasteners in a base, the combination of: a bed for receiving said base; a conveyor for moving said base along said bed; punch means for forming fastener receiving holes in said base; rotary support means on said bed for engaging and supporting the underside of said base immediately adjacent said holes during the driving of said fasteners therethrough; and fastener driving means for inserting said fasteners in said holes and driving them through said base.

3. In an apparatus for inserting fasteners in a base, the combination of: a bed for receiving said base; a conveyor for moving said base along said bed; punch means for forming fastener receiving holes in said base; support means on said bed for supporting the underside of said base adjacent said holes during the driving of said fasteners therethrough, said support means including a plurality of recesses for receiving portions of said fasteners after they are driven through said base; and fastener driving means for inserting said fasteners in said holes and driving them through said base.

4. In an apparatus for inserting fasteners in a base, the combination of: a bed for receiving said base; a conveyor for moving said base along said bed; punch means for forming fastener receiving holes in said base; rotary support means

on said bed for supporting the underside of said base adjacent said holes during the driving of said fasteners therethrough, said support means including a plurality of recesses for receiving

5 portions of said fasteners after they are driven through said base; and fastener driving means for inserting said fasteners in said holes and driving them through said base.

5. In an apparatus for inserting fasteners in 10 a base, the combination of: a supporting frame; a reciprocable carriage mounted on said frame for movement between a first position and a second position; a bed mounted on said frame for receiving said base; a conveyor for moving said base along said bed; punch means mounted on said carriage for forming fastener receiving holes in said base; fastener driving means mounted on said carriage for inserting said fasteners in said holes and driving them through said base; and support means secured intermediate the ends of said bed for supporting and engaging successive portions of the underside of said base immediately adjacent said holes during the driving of said fasteners therethrough.

6. In an apparatus for inserting fasteners in a base, the combination of: a supporting frame; a reciprocable carriage mounted on said frame for movement between a first position and a second position; a bed mounted on said frame for receiving said base; a conveyor for moving said base along said bed; punch means mounted on said carriage for forming fastener receiving holes in said base; fastener driving means mounted on said carriage for inserting said fasteners in said holes and driving them through said base; support means on said bed for supporting the underside of said base adjacent said holes during the driving of said fasteners therethrough; and depth adjustment means adjacent said bed

40 for adjusting the extent of projection of said fasteners from said base, said depth adjustment means including anvil means on said bed and a reciprocable hammer on said carriage for engaging said base during the adjustment of said fasteners on said anvil means.

7. In an apparatus for inserting fasteners in a base, the combination of: a supporting frame; a reciprocable carriage mounted on said frame for movement between a first position and a second position; a bed mounted on said frame for receiving said base; a conveyor for moving said base along said bed; punch means mounted on said carriage for forming fastener receiving holes in said base; release means mounted on said carriage in juxtaposition to said punch means for temporarily rendering said punch means ineffective; fastener driving means mounted on said carriage for inserting said fasteners in said holes and driving them through said base; support

50 means on said bed for supporting the underside of said base adjacent said holes during the driving of said fasteners therethrough; and depth adjustment means adjacent said bed for adjusting the extent of projection of said fasteners from said base.

8. In an apparatus for inserting fasteners in a base, the combination of: a supporting frame; a reciprocable carriage mounted on said frame for movement between a first position and a second position; a bed for receiving said base mounted on said frame adjacent said carriage; a conveyor on said frame operatively connected to said carriage for translating said base along said bed; punch means mounted on said carriage for forming fastener receiving holes in said base;

fastener driving means mounted on said carriage for inserting said fasteners in said holes and driving them through said base; and support means fixedly secured to said bed intermediate the ends thereof and movable by said fasteners after they are driven through said base about its point of securement to said bed.

9. In an apparatus for inserting fasteners in a base, the combination of: a supporting frame; a reciprocable carriage mounted on said frame for movement between a first position and a second position; a bed for receiving said base mounted on said frame adjacent said carriage said bed having a recess intermediate its ends; an intermittently operable, reciprocable conveyor on said frame operatively connected to said carriage for sliding said base along said bed in direct contact therewith and over said recess; punch means mounted on said carriage for forming fastener receiving holes in said base; fastener driving means mounted on said carriage for inserting said fasteners in said holes and driving them through said base; and support means secured in said recess for engaging said base adjacent said holes as said fasteners are driven therein.

10. In an apparatus for inserting fasteners in a base, the combination of: a supporting frame; a reciprocable carriage mounted on said frame for movement between a first position and a second position; a bed for receiving said base mounted on said frame adjacent said carriage; an intermittently operative conveyor for translating said base along said bed; punch means mounted on said carriage for forming fastener receiving holes in said base; fastener driving means mounted on said carriage for inserting said fasteners in said holes and driving them through said base; and support means secured intermediate the ends of said bed for supporting and engaging the underside of said base immediately adjacent said holes during the driving of said fasteners therethrough, said support means being operable by the movement of said fasteners along said bed.

11. In an apparatus for inserting fasteners in a base, the combination of: a supporting frame; a reciprocable carriage mounted on said frame for movement between a first position and a second position; a bed for receiving said base mounted on said frame adjacent said carriage, said bed having a recess intermediate its ends; a conveyor on said frame operatively connected to said carriage for translating said base along said bed; punch means mounted on said carriage for forming fastener receiving holes in said base; fastener driving means mounted on said carriage for inserting said fasteners in said holes and driving them through said base; and support means in said recess for engaging and supporting the underside of said base immediately adjacent said holes during the driving of said fasteners therethrough.

12. In an apparatus for inserting fasteners in a base, the combination of: a supporting frame; a reciprocable carriage mounted on said frame for movement between a first position and a second position; a bed for receiving said base mounted on said frame adjacent said carriage; an intermittently operable conveyor on said frame operatively connected to said carriage for translating said base along said bed; punch means mounted on said carriage for forming fastener receiving holes in said base; fastener driving means mounted on said carriage for in-

serting said fasteners in said holes and driving them through said base; and support means secured intermediate the ends of said bed for engaging and supporting successive portions of the underside of said base immediately adjacent said holes during the driving of said fasteners therethrough.

13. In an apparatus for inserting fasteners in a base, the combination of: a supporting frame; a reciprocable carriage on said frame; cam means carried on said carriage and reciprocable therewith; a bed mounted on said frame for receiving said base; a reciprocable conveyor for moving said base along said bed, said conveyor including engagement means automatically releasable from said base to permit said conveyor to be reciprocated with respect to said base to urge said base along said bed; and cam follower means on said conveyor engageable with said cam for moving said conveyor with respect to said bed.

14. In an apparatus for inserting fasteners in a base, the combination of: a supporting frame; a reciprocable carriage on said frame; cam means carried on said carriage and reciprocable therewith; a bed mounted on said frame for receiving said base; a reciprocable conveyor for moving said base along said bed, said conveyor including engagement means automatically releasable from said base to permit said conveyor to be reciprocated with respect to said base to urge said base along said bed; cam follower means on said conveyor engageable with said cam for moving said conveyor with respect to said bed; and punch means for forming fastener receiving holes in said base.

15. In an apparatus for inserting fasteners in a base, the combination of: a supporting frame; a reciprocable carriage on said frame; cam means carried on said carriage and reciprocable therewith; a bed mounted on said frame for receiving said base; a reciprocable conveyor for moving said base along said bed, said conveyor including engagement means automatically releasable from said base to permit said conveyor to be reciprocated with respect to said base to urge said base along said bed; cam follower means on said conveyor engageable with said cam for moving said conveyor with respect to said bed; punch means for forming fastener receiving holes in said base; and fastener driving means for inserting said fasteners in said holes and driving them through said base.

16. In an apparatus for inserting fasteners in a base, the combination of: a supporting frame; a reciprocable carriage on said frame; cam means carried on said carriage and reciprocable therewith; a bed mounted on said frame for receiving said base; a reciprocable conveyor for moving said base along said bed, said conveyor including engagement means automatically releasable from said base to permit said conveyor to be reciprocated with respect to said base to urge said base along said bed; cam follower means on said conveyor engageable with said cam for moving said conveyor with respect to said bed; and punch means mounted on said carriage for forming fastener receiving holes in said base.

17. In an apparatus for inserting fasteners in a base, the combination of: a supporting frame; a reciprocable carriage on said frame; cam means carried on said carriage and reciprocable therewith; a bed mounted on said frame for receiving said base; a reciprocable conveyor for moving said base along said bed, said conveyor including engagement means automatically releasable

from said base to permit said conveyor to be reciprocated with respect to said base to urge said base along said bed; cam follower means on said conveyor engageable with said cam for moving said conveyor with respect to said bed; punch means mounted on said carriage for forming fastener receiving holes in said base; and fastener driving means mounted on said carriage for inserting said fasteners in said holes and driving them through said base.

18. In an apparatus for inserting fasteners in a base, the combination of: a supporting frame; a reciprocable carriage on said frame; a bed mounted on said frame for receiving said base, a reciprocable conveyor for moving said base along said bed, said conveyor including engagement means at its opposite ends adjacent opposite ends of said bed for automatically engaging and releasing said base to permit the reciprocation of said conveyor with respect to said base to urge said base along said bed; and fastener driving means mounted on said carriage for inserting said fasteners in said base and driving them therethrough.

19. In an apparatus for inserting fasteners in a base, the combination of: a supporting frame; a reciprocable carriage on said frame; an elongated bed mounted on said frame for receiving said base in sliding relationship; a reciprocable conveyor for sliding said base along said bed, said conveyor including a conveyor carriage having an elongated extension attached to one end thereof and paralleling said bed, said conveyor carriage and said elongated extension each being provided with automatic engaging means for automatically engaging and releasing said base to urge it along said bed; and fastener driving means mounted on said carriage for driving said fasteners into said base.

20. In an apparatus for inserting fasteners in a base, the combination of: a supporting frame; a reciprocable carriage on said frame having cam means secured thereto; an elongated bed mounted on said frame for receiving said base; a reciprocable conveyor for moving said base along said bed, said conveyor including cam follower means engageable with the cam means on said carriage for moving said conveyor in one direction with respect to said bed; spring means for moving said conveyor in the other direction with respect to said bed to accomplish the reciprocation of said conveyor to urge said base along said bed; and fastener driving means secured to said carriage for driving said fasteners into said base.

21. In an apparatus for inserting fasteners in a base, the combination of: a supporting frame; a reciprocable carriage mounted on said frame for movement between a first position and a second position; a bed for receiving said base mounted on said frame adjacent said carriage; a reciprocable conveyor mounted on said frame adjacent said bed for slidably translating said base along said bed, said conveyor including engagement means for automatically engaging said base to slide said base along said bed; fastener driving means mounted on said carriage for inserting said fasteners in said base; and hopper means mounted on said frame adjacent one end of said bed, said hopper means having an adjustable end wall to permit the adjustment of said hopper means to accommodate bases of different lengths and a fixed end wall provided with an adjustable opening to permit one of the bases deposited in said hopper means to be extracted therefrom by the automatic engagement means on said con-

veyor to cause the extracted base to be slid along said bed by said conveyor.

22. In an apparatus for inserting fasteners in a base, the combination of: a bed for receiving said base; a conveyor for moving said base along said bed; fastener inserting and driving means for inserting said fasteners in said base and driving them therethrough; and support means secured intermediate the ends of said bed for supporting the underside of said base immediately adjacent the areas where said fasteners are driven through said base, said support means including a plurality of recesses for receiving portions of said fasteners after they have been driven through said base and being movable about its point of securedment to said bed.

23. In an apparatus for inserting fasteners in a base, the combination of: a bed for receiving said base; a conveyor for moving said base along said bed; fastener inserting and driving means for inserting said fasteners in said base and driving them therethrough; and rotary support means on said bed for supporting the underside of said base immediately adjacent the areas where said fasteners are driven through said base, said rotary support means including a plurality of recesses for receiving portions of said fasteners after they have been driven through said base, said rotary support means having positioning means operatively engageable therewith for aligning said recesses with said base areas to permit the passage of said portions of said fasteners therethrough.

24. In an apparatus for inserting fasteners in a base, the combination of: a bed for receiving said base; a conveyor for moving said base along said bed; fastener inserting and driving means for inserting said fasteners in said base and driving them therethrough; and a rotatable supporting wheel secured in said bed for engagement with the underside of said base as it is moved therewith by said conveyor, said supporting wheel having a plurality of recesses provided in the periphery thereof engageable by portions of said fasteners driven through said base, said supporting wheel being rotatable by the longitudinal movement of the portion of a fastener in one of said recesses to cause another of said recesses to be disposed in registry with the portion of a succeeding fastener driven through said base.

25. In an apparatus for inserting fasteners in a base, the combination of: a bed for receiving said base; a conveyor for moving said base along said bed; fastener driving means for inserting said fasteners in said base and driving them therethrough; and a rotatable supporting wheel secured in said bed for engagement with the underside of said base as it is moved therewith by said conveyor, said supporting wheel having a plurality of recesses provided in the periphery thereof engageable by portions of said fasteners driven through said base, said supporting wheel being rotatable by the longitudinal movement of the portion of one of said fasteners in one of said recesses to cause another of said recesses to be disposed in registry with the portion of a succeeding fastener driven through said base, said wheel having positioning means operatively engageable with the periphery thereof for accurately registering said recesses with said portions of said fasteners as they are driven through said base.

26. In an apparatus for inserting fasteners in a base, the combination of: a supporting frame;

a reciprocable carriage mounted on said frame for movement between a first position and a second position; a bed mounted on said frame for receiving said base; a conveyor for moving said base along said bed; fastener driving means mounted on said carriage for driving said fasteners through said base; and depth adjustment means adjacent said bed for adjusting the extent of projection of said fasteners from said base, said depth adjustment means including hammer means secured to said carriage and engageable with said base and anvil means secured to said bed and engageable with the ends of said fasteners simultaneously with the engagement of said base by said hammer means.
